UNITED STATES PATENT OFFICE.

FELIX D. DOUBLEDAY, OF NEW YORK, N. Y.

CIGARETTE AND CIGAR LIGHTER.

Application filed November 19, 1926. Serial No. 149,494.

This invention relates to improvements in cigarette and cigar lighters, and has for an object, by a novel combination of parts, to provide a continuous strip match friction 5 lighter free from all liquid fuels.

It is also an object of my invention to provide a lighter capable of sustaining a prolonged illumination by simply turning up more and more of the match material for 10 lighting one's way in the dark, and to serve for many other useful purposes.

With the above objects, and certain other objects in view which will become apparent as the description proceeds, my invention 15 consists in the novel parts, and combination of parts, all as hereinafter will be more fully described and particularly pointed out in the claims.

Referring to the accompanying drawings 20 forming a part of this specification in which like numerals designate like parts in all the views:—

Figure 1 is a section cut through the side of one of my lighters.

25 Figure 2 is another section cut through one of my lighters along the line *a, b*, of Figure 1.

Figures 3, 4, 5, and 6, are different designs 30 of my continuous strip adapted to be coiled up upon a hub member and be inserted in the casing of the lighter.

Figure 7 is an elevational view of one of my lighters, closed, as when carried in the pocket ready for use.

35 Figure 8 is a top view of my lighter closed, with certain of its elements shown in dotted line.

Figure 9 is a top view of a modification of one of my friction wheels.

40 Figure 10 is an edge view of this modified friction wheel.

With further reference to Figure 1. 15 is the metal of the casing, 16 is the edge of a coil of one of my match strips, 17 is a 45 wooden hub piece comprising a slot-way 18 mounted on a shaft 19, with a key 20 adapted to engage with and turn the hub 17. One end of my match strip 16 is glued, or otherwise suitably attached to this wooden hub 50 member 17 and the other end of the match strip passes out of the case between the metal guide member 21 and the side of the case with the projecting finger 22. 23 is a thumb wheel mounted on the stud 24 adapted 55 to slide in the slot-way 25 to come into contact with the end of the match strip as it

protrudes from the case and rests against the projecting finger 22. The stud 24 is held back by the spring 25', holding the thumb wheel 23 out of contact with the 60 match strip, and the said spring is anchored at its stationary end by the stud 26. This thumb wheel may have a roughened periphery 26' in the form of small teeth or the periphery may be charged with a safety- 65 match lighting composition.

With further reference to Figure 2. The same parts as already illustrated and described may be easily identified by the numerals, and in addition certain other features 70 are also shown. 27 is a finger and thumb wheel adapted to turn the shaft 19 and to feed the match-strip up through the casing as desired by the user. 28 is a stud carried by the wall of my lighter, and adapted to 75 receive and hold in convenient position until required for use, an extra or spare coil of match material. 30 is a hinged side of my casing adapted to swing out and open on the hinge 31 and also adapted to be held 80 in closed position by the lip and little projecting bump 32 engaging a small recess in the bottom of the casing.

I have shown at the left of the view in dotted lines, the manner in which the casing 85 swings open to facilitate the introduction of my coils of match material.

With further reference to Figure 3. 16 is the edge of the pasteboard strip or other suitable combustible material either impregnated or unimpregnated with wax, or saltpeter or both for example to promote and maintain combustion in both still air and in the wind. 32 and 33 are strips of match composition, and match lighting composition 95 respectively, 32 being the match composition corresponding with the substances in the head of a safety match, and 33 is the igniting composition, corresponding with the substances on the side of a safety-match 100 box.

In my present invention my friction wheel may be of metal and may bring the compositions of the two parallel strips together under the rotating action and friction of 105 its roughened periphery, as one means of securing the desired results.

With further reference to Figure 4. The match composition is shown in a single and simple straight strip.

With further reference to Figure 5. The match composition is shown inserted in

spaced recesses cut out of the strip of combustible material.

With further reference to Figure 6. The match composition is shown inserted in a simple and continuous strip, but between two thicknesses of material adapted to be pasted together, and to be subsequently cut through by the roughened periphery of the thumb friction wheel.

10 With further reference to Figure 9. 26' is the periphery of a composition-impregnated wheel, fibre, paper or felt for example, treated with safety-match lighting composition, 23 is a retaining metallic disc, and 24 is the stud member.

With further reference to Figure 10. 26' is the periphery of a pack of composition-impregnated discs, 23 retaining metallic discs, and 24 the stud member.

20 To operate, after loading my lighter, camera fashion, with the match strip, whether of ordinary phosphorus match-head composition, or of safety match-head composition, it is only necessary to push 25 over and revolve the thumb wheel by the thumb of the user, in contact with the match strip, and when lighted by the friction thus set up, to allow the spring member to draw the thumb wheel quickly out of the zone of 30 the flame, and then to turn up the light through the agency of the finger and thumb wheel at the side of the casing. The continuous match may be turned up as much as desired. Upon ceasing to turn the match 35 strip up, it will burn down to the metal finger 22 and the guide member 21 which between them provide a narrow passage through which the flame cannot follow. The match strip is thus extinguished at the narrow 40 orifice here provided.

When I use a continuous strip of match composition material, I secure an active and flaring flame difficult to extinguish in the wind, and when I use a strip of combustible material with spaced and inserted match composition material, I secure a flame comparable with that of the ordinary paste-board match. Whereas I have shown and described one design of lighter, it is evident 50 that I may alter the design in a wide variety of ways without departing from the spirit of the invention.

The continuous match strip may be manufactured attached to its little hub-member 55 by glue as described, and the free end adapted to be lighted may be temporarily attached to an outer convolution also by a patch of glue, and the whole coiled strip be sold in a small and compact moisture proof box of any desired material.

Having described my invention, I claim:—

1. A pocket lighter as described comprising a continuous coiled strip of combustible material, match composition applied thereon 60 in a plurality of strips, one of the said strips

consisting of a safety-match composition, and another of the strips consisting of a complementary safety-match friction kindling composition, a casing, and a friction device on the casing adapted to be advanced 70 into moving contact with the strips of match composition.

2. A pocket lighter comprising a continuous coiled strip of combustible material, applied match composition thereon adapted to 75 be kindled by friction, a central core member therefore, a shaft and a key adapted to mount and revolve the said core member, a member adapted to revolve the shaft, a casing with a removable wall adapted to open 80 and close said wall having an opening with a slot-way therein, said wall adapted to support the said shaft core and coiled strip, an exit to an end of said coiled strip, and a friction wheel on the casing adapted to advance into revolving frictional engagement with the said strip of combustible material. 85

3. A pocket lighter as described comprising a continuous coiled strip of combustible material, applied match composition thereon 90 adapted to be kindled by friction, a casing, means for advancing an end of said coiled strip through an opening in the casing, a friction wheel, a stud, a slot-way and a spring adapted to move the stud and friction wheel in said slot-way, and a roughened periphery on the said friction wheel. 95

4. A pocket lighter comprising a continuous coiled strip of combustible material, applied match composition thereon adapted to 100 be kindled by friction, a casing with an aperture and an extension member adapted to support one end of the said strip against lateral pressure, means for advancing an end of said coiled strip through the aperture in 105 the casing, and a friction wheel adapted to move into revolving contact with the end of the strip of combustible material and to press it against the said extension member of the case. 110

5. A pocket lighter comprising a continuous coiled strip of combustible material, applied match composition thereon adapted to be kindled by friction, a casing, means to feed said strip out of said casing, and a 115 rotatable friction device slidably mounted on the casing for igniting said composition when rotated thereagainst.

6. A pocket lighter comprising a strip of combustible material with applied match composition thereon, an apertured hub on which said strip is coiled, a casing one of the walls of which is movable to permit insertion of a coiled strip, a stud on one of the stationary casing walls to fit a hub and support a coiled strip, a shaft mounted on the movable wall of said casing said shaft adapted to receive and revolve the hub of a coiled strip, an extension of one of the walls of said casing adjacent an opening therein 120 125 130

through which said coiled strip may pass, and a friction wheel adapted to be moved into contact with the exposed end of said strip to ignite the match composition by 5 pressure against said extension.

7. A pocket lighter comprising a continuous coiled strip of combustible material, applied match composition thereon adapted to be kindled by friction, a casing, means to 10 feed said strip out of said casing, and a rotatable friction device carried by a spring controlled pin extending through a slot in the wall of said casing, said device adapted to be moved into contact with said strip for 15 igniting said composition.

8. A pocket lighter comprising a continuous coiled strip of combustible material, applied match composition thereon adapted to be kindled by friction, a casing, means to feed said strip out of said casing, and means 20 for igniting said composition said means including a friction disc normally held out of contact with said strip but adapted to be bodily moved into contact therewith and rotated while in said contact to cause ignition of said composition. 25

Signed at New York city, in the county of New York and State of New York, this 15th day of September, A. D. 1926.

FELIX D. DOUBLEDAY.
